UNITED STATES PATENT OFFICE.

WALLACE H. CAMP, OF WATERBURY, CONNECTICUT, ASSIGNOR TO THE
SCOVILL MANUFACTURING COMPANY, OF SAME PLACE.

POST-OFFICE-BOX DOOR.

SPECIFICATION forming part of Letters Patent No. 224,141, dated February 3, 1880.

Application filed December 26, 1879.

To all whom it may concern:

Be it known that I, WALLACE H. CAMP, of Waterbury, in the county of New Haven and State of Connecticut, have invented a new Improvement in Post-Office-Box Doors; and I do hereby declare the following, when taken in connection with the accompanying drawings and the letters of reference marked thereon, to be a full, clear, and exact description of the same, which drawings constitute part of this specification, and represent, in—

Figure 1, a front view; Fig. 2, a transverse section on line *xx*; Fig. 3, a section on line *zz*.

This invention relates to an improvement in that class of post-office-box doors which are made from metal, and which are provided with glass panels, so that the interior of the box may be seen from the outside when the door is closed.

In the usual construction it has been found necessary to form a guard outside the glass to prevent access to the box should the glass be broken. This guard, which is in the form of an open metal-work, prevents cleaning the glass and otherwise interferes with properly seeing the interior of the box.

The object of this invention is to avoid this outside guard; and it consists in the construction, as hereinafter described, and particularly recited in the claim.

A represents the door-frame, and *B* the four sides of the door, hinged to the frame in the usual manner. The frame is made with a rabbet, *a*, upon the inside, within which the glass *C* will rest.

Across the center of the door, and in rear of the glass, is a bar, *D*, this bar being designed to receive the lock. The glass *C* is a thick plate,

and made so as to pass between the bar *D* and the rabbet *a*, as seen in Fig. 2. At the center 40 or opposite the bar *D* the glass is perforated, as at *d*, and through this a flanged sleeve, *e*, is introduced and screwed into the bar *D*, or otherwise attached to it, so that the flange will bear upon the outside of the glass and 45 form a finish around the perforation in the glass. This sleeve is designed to inclose the hub of the lock, which is placed upon the bar so that the hub will pass through the sleeve *e* and be secured to the bar *D*. 50

Instead of the flanged sleeve *e*, the hub of the lock may pass through the bar *D* and the perforation in the glass, and then a collar secured to the hub will cover the joint, the essential feature of the invention being that 55 there shall be an opening through the glass through which the lock may be reached.

By this construction the entire space within the frame may be filled by a single pane of thick glass, giving an unobstructed view of the interior of the box, and also enabling the exterior of the glass to be readily cleaned. 60

I claim—

A metallic door for post-office boxes having an opening, with the lock-bar in rear, combined with a single glass panel introduced inside the door, but outside the said lock-bar, and constructed with a perforation corresponding with the hub of the lock, substantially as described. 65

WALLACE H. CAMP.
